SIGNALING APPARATUS.

1,196,429.

Specification of Letters Patent. Patented Aug. 29, 1916.

Application filed February 9, 1911. Serial No. 607,618.

To all whom it may concern:

Be it known that I, THEODOR BRUGER, a citizen of the German Empire, and a resident of Frankfort-on-the-Main, Prussia, Germany, have invented certain new and useful Improvements in Signaling Apparatus, of which the following is a specification.

This invention relates to signaling apparatus of the type adapted for use with monophase or polyphase electrical currents, and has for its object an improved signaling apparatus of this character wherein means are provided for obtaining an exact, clear, and continuous transmission, to long distance, of the position of the transmitter over the whole range of a complete circle or multiple thereof.

To this end, the invention contemplates a signaling apparatus including a novel means of utilizing out-of-phase currents for transmitting signals to a distance, said means comprising the combination of a phase-regulating transmitter, with a novel construction of phase-indicator or receiver.

Though susceptible of embodiment in different forms of construction, and different arrangements of circuits, certain preferable and practical embodiments of the invention are illustrated in the accompanying drawings, in which—

Figure 1 is a diagrammatic illustration of the invention in its application to a polyphase net-work. Fig. 2 is a diagrammatic illustration of the manner in which the receiver operates. Fig. 3 is a diagrammatic plan view showing the structural characteristics and connections of the transmitter shown in Fig. 1. Fig. 4 is a detail in perspective of the novel receiver construction shown in Figs. 1 and 4.

Like reference characters designate corresponding parts in the several figures of the drawings.

The means for carrying the invention into effect may assume various forms. However, as one form of illustration, particular reference is made to the diagram of Fig. 1 of the invention showing its application to a polyphase net work. Different forms of trans-

mitters may be employed, but it will be understood that the transmitter must be able, by its adjustment, to continually vary the phase of the long distance current; and the receiver must be so arranged that, by the influence of a rotating field upon a mono-phase alternating field of equal frequency, the latter varies its position in accordance with its phase. Hence, for operating the phase regulator, as well as for generating the rotating field in the receiver, currents may be used which are taken from a polyphase net-work, as shown in Fig. 1. In this form of construction, the transmitter is designed as transformer with ring-shaped primary and secondary which are rotatable with relation to one another. Figs. 1 and 3 illustrate both the construction and the connections of the transmitter. Referring thereto, it will be observed that the primary coil P^1 is wound on the inner iron ring and connected to the three wires of the three-phase circuits I, II, III at three points displaced with relation to one another through 120° . The secondary coils s^1 , closed in itself, surrounds the outer iron ring and carries two conductors fixed at a and b and leading to the receiver. The whole secondary ring is rotatable concentrically to the primary ring, and when turned the collecting points vary their position relatively to the fixed primary ring respectively, to the respective points where the current is supplied.

As will be seen, the phase of the current collected at $a-b$ depends on the position of these collecting points with relation to the fixed connecting points of the primary ring, and, consequently, by turning the said secondary ring, the phase of the long distance current may be continuously varied with relation to one of the three primary currents. Obviously, besides the induction effect, there is also a turning effect between the fixed primary and movable secondary rings which varies with the position of the two rings in relation to each other and depends on the connections of the current supplied. This torque might be inconvenient if, for the adjustment of the movable transmitter, only very feeble forces are available.

It can, however, be rendered non-effective by employing two systems of transformers for the transmitter instead of one only, the secondaries of the double system being coupled together while the primaries are connected with the mains of the three phase circuit in such a manner that the torques produced in the upper and lower systems are directly opposed one to another, and compensate each other. As mentioned already, the long distance current is taken off at the points $a-b$ of the secondary coil s^1 , while at two points $a'-b'$, corresponding with $a-b$, a resistance is connected to the ring coil s^2 turning in unison with s^1 , the value of this resistance being equal to that of the receiver coil s connected with $a-b$. By this arrangement is obtained the conditions of current perfectly equal in both systems $p^1 s^1$ and $p^2 s^2$, and these latter constitute in a certain sense an astatic system, for the adjustment of which inner electromagnetic forces need not be overcome.

The receiver of the construction illustrated in Figs. 1 and 4 has a small electromagnet, shown in Fig. 4. The light body e of thin sheet iron or wire is connected with the axis of rotation and consists of a cylindrical or quadrangular tube with semicircular pole surfaces, which are bent vertically away to opposite sides of the axis of the magnet at the top and at the bottom thereof. The iron body is so magnetized by the fixed coil s that radially directed fields of force are produced in the pole surfaces. This receiver also includes two crossed out-of-phase fields represented by coils f^1 and f^2 , produced by the alternating current of the two mains. The manner in which this receiver operates is diagrammatically illustrated in Fig. 2. In this diagram r represents the rotating field vector of the system, which, with nearly constant value, turns during a period through the circle a, b, c , whereas g is the field vector of the monoaxial moving coil, which, in a certain position, while varying its value and polarity, oscillates during a period. Obviously, the field vector g , or moving coil, producing the field, corresponding to g , will adjust itself so that, at the moment in which g attains its positive or negative maximum value, this vector will coincide with the rotating field vector r . If, therefore, on closing the long distance current, the moving coil of the receiver is in such a position that its alternating field oscillates in the direction $a-c$ and the vector r has the position $a-b$, and g at the same time attains its maximum at $a-a$, then $a-a$ will be turned in the direction $a-b$, for which, as regards time, the positive as well as the negative maximum of g coincides with r . If, however, the long distance current is out-of-phase, then g attains its maximum value at a time different from that

which previously prevailed, and the position of r corresponding to this moment is displaced, with respect to $a-b$, through the phase angle φ . Hence the vector g , and the moving coil of the receiver, will simultaneously move through the angle φ with respect to the former direction $a-b$ and assume the new position of equilibrium, where again the maximum values of g coincide with r . It is evident, therefore, that, in the arrangement of the receiver as described above, the adjustment of the moving coil connected with the needle Z depends only on the phase of the long distance current, and, on variation of this phase, varies, theoretically, independently of current, pressure, and frequency over a circular scale through a corresponding angle. Now, as the phase of the long distance current clearly depends on the position of the transmitter, accordingly there is a direct definite relation between the latter and the position of the receiver needle which can be directly used for long distance transmission.

The systems supplement one another to a circular surface and are in any position influenced by the whole of the lines of force of the field produced by f^1 and f^2 in such a manner that slight faults of symmetry of the latter do not affect the position of the pointer of the receiver. The phase displacement between the fixed coils f^1 and f^2 , necessary for producing the rotating field, is obtained by connecting one of these coils by means of a star-connected resistance σ to the star voltage of phase 1 of the three-phase net-work. On the other hand, the normal voltage for the second coil is collected from the two other branches of the zero resistance; that is to say, between phases 2 and 3, at such a distance from zero that the second coil supplies a field of equal intensity to the first. It would, of course, be possible to make the connection in the known manner, wherein the fixed rotating field results from the coöperation of three coils fed directly from the three-phase net-work.

I claim:

1. A signaling system of the character herein referred to and wherein three-phase current taken from a net-work is used, the same including in combination with a transmitter, a receiver having an inner rotary armature and a rotating field produced by only two field coils, the currents of which are displaced through 90° with respect to each other by directly connecting up to a star-voltage, and wherein the oppositely situated main voltage is taken from a zero resistance, the said currents being made equal to each other by connecting the wires fed by the main current to two symmetrical spots situated nearer to the zero point.

2. A signaling apparatus of the class described including a transmitter, the current

lines, and a receiver comprising two crossed out-of-phase fields and an electromagnet placed inside of said fields and consisting of a fixed coil, and a movable part having 5 a pointer and oppositely located pole pieces respectively projecting to opposite sides of the magnet.

In testimony whereof I have affixed my signature in presence of two witnesses.

THEODOR BRUGER.
